SEGMENTAL ABRASIVE WHEEL

Application filed May 19, 1924. Serial No. 714,322.

Our invention relates to grinding wheels and more particularly to a wheel suitable for grinding wood pulp.

Abrasive wheels for grinding pulp must be very large in size and be able to withstand enormous strains due to the weight and pressure of the logs being ground, as well as to the heat produced by the abrading friction. An attempt has been made to use ceramic bonded artificial abrasives for such wheels but it has been found that they break easily or their corners chip off, thus making the use of such wheels expensive. Owing to problems met in manufacturing, it has been found desirable to make the pulp grinding stone of a number of segments, and to clamp these together to form the complete wheel; but the necessity for driving the stone under the enormous restraining pressure of heavy logs held against the wheel has made it difficult to mount the segments on a spindle and clamp them between driving flanges without increasing the liability of breakage.

It is, accordingly, an object of our invention to provide an improved grinding wheel of this type which may be economically manufactured and easily assembled, which will give a long and efficient life of service, and which is so constructed that the abrasive material will not become cracked or broken due to the heat expansion or the frictional strains of normal usage.

It is a further object of our invention to provide an improved mounting for the segments of a wheel whereby the segments may be held rigidly in position under a clamping pressure which is so uniformly distributed that the driving flanges may be adjusted tightly in place without serious results.

With these and other objects in view, as will be intimated in the following enclosure, our invention resides in the combination of parts set forth in the specification and covered by the claims appended hereto.

Referring to the drawings, in which like reference numerals indicate like parts:

Fig. 1 is a section on the line 1—1 of Fig. 2 showing one embodiment of our invention;

Fig. 2 is a vertical central section through the grinding wheel; and

Fig. 3 is an enlarged sectional detail showing the mounting of the abrasive segments.

One embodiment of our invention may comprise a grinding wheel made up of a plurality of rows of closely positioned abrasive segments mounted on a rotatable support, such as a drum. These segments may be secured in position by means of clamping flanges or plates engaging the exposed faces of the end segments on the wheel which are so mounted that they may be adjustably moved toward each other to clamp the segments firmly therebetween. The segments are so shaped that they will lie close together adjacent to the cylindrical grinding surface of the wheel; and between the inner faces of adjacent segments is a clamping or friction member which serves when the clamping flanges are adjusted into position to frictionally or otherwise engage the inner sides of the segments and aid in holding them in position. The clamping or friction member, which may be in the shape of a ring mounted in an annular groove formed between adjacent faces of the segments, is freely movable parallel with the axis of the wheel and relative to the surface of the drum, so that the pressure of the clamping flanges may be distributed throughout the wheel. The surface of the wheel is made up of a large number of small abrasive segments to minimize the liability of breakage from heat expansion; and in order that the segments may be supported laterally and protected from forces tending to break the wheel, the crevices are filled adjacent to the surface of the wheel with a filler, and preferably one of a cementitious nature, which will unite with the sides of the segments and form them into an integral solid body.

As shown in the drawings, a wide faced wheel may be formed of a plurality of disk shaped rows 10 of segments which are so formed and arranged as to provide a cylindrical grinding surface 11. The segments 12 may be individually shaped, as shown in the drawings, as quadrants or in other suitable forms, and their inner surfaces are made concave so as to form an internal cylindrical surface 13 which will fit on a rotatable sup-

port and so position the segments properly.

The rotatable support may be shaped as a large drum 15 which has an outer cylindrical surface, and this drum is in turn removably mounted on a spindle or driving shaft 16 by means of the annular webs 17 which have a sliding fit on the shaft.

In order to clamp in position these rows 10 of abrasive segments and to drive them rotatively, we provide end flanges or driving members 20 which have central openings 21 screw threaded to the spindle 16. The threads of the two driving flanges are so disposed, one a right-hand thread and the other a left-hand thread, that rotation of the spindle 16 in normal operation tends to tighten the hold of the flanges upon the abrading elements. As illustrated, these flanges project beyond the outer periphery of the drum and the assembled abrading disks are of such width that they project slightly beyond the ends of the drum so that the flanges may be clamped against the outer surfaces of the end segments.

25 In order to transmit the clamping pressure uniformly throughout the abrading wheel and to prevent breakage of the same, we provide frictional driving rings 24, whose inner peripheries are such as to fit upon the outer surface of the drum and the outer peripheries are as great as those of the driving flanges 20. In order that the adjacent edges of the rows of abrasive segments may be close together, we cut a groove 25 in the inner faces of each 30 segment in one row of such a size and depth that a ring 24 may fit therein. These rings may have parallel plane faces 26 and 27, but we prefer to make them slightly wedge shaped in order to assist in holding the abrasive segments in place, and particularly in case of breakage of any of the segments. To this end, each groove 25 is made slightly shallower adjacent the inner periphery of the wheel, and each ring 24 is provided with a tapering face 35 on one side to fit the groove. The other side of the ring is made parallel with the plane face 29 of the other side of the adjacent row of segments which lies in a diammetrical plane of the wheel.

50 Since the two faces of each adjacent row of segments should be accurately made, we may provide each side 29 with a central raised portion 30 which may be trued off to the desired extent to make a careful driving fit. In 55 order that all abrasive segments may be made alike, it will be observed that one-half of them are shown in Fig. 1 as facing in one direction and the other half in the other, so that at the center of the wheel, two of the wedging and 60 driving rings are employed.

It will be seen therefore, that we have provided a construction in which the abrasive segments are held in place and rotated by the friction of the rings 24 and the end 65 clamping flanges 20. The rows of abrasive

segments make close fits with each other and with the rings, so that the pressure is evenly distributed and each segment is subjected to the same driving forces. This arrangement of frictional driving and locking rings between each pair of adjacent abrasive segments provides such a mounting that the wheel may be subjected to the enormous pressures involved in grinding wood pulp without danger of breaking the wheel under normal usage.

This type of grinding wheel is particularly adapted for grinding wood pulp in which operation logs are held against the peripheral surface of the wheel under high pressure. If the wheel is intended for such severe usage, we propose to fill the crevices, and particularly adjacent to the cylindrical grinding surface, with a filler, and preferably a cementitious filler, such as cement, which will adhere to the segments and unite them into a rigid, unitary wheel structure. This filler supports the sides of the segments so that any lateral thrust will be transmitted easily from one segment to another and thus be absorbed without endangering the wheel. Also, it prevents slivers of wood or the like from lodging in the crevices between the segments and so passing through the grinding zone and thus producing an inferior grade of wood pulp. Moreover, if the crevices between the segments are filled to the outer cylindrical surface of the wheel, there are no projections or depressions for the logs to bump or strike forcibly against, and sooner or later break off chips from the wheel. In this way the life of the wheel is materially lengthened. It is also to be explained that the clamping or friction members 24 may be made of suitable metals, such as lead or other soft materials, which may have a good driving hold on the abrasive segments or otherwise serve the purposes specified.

Having thus described our invention, what we claim as new and desire to secure by Letters Patent is:

1. A wood pulp grinding wheel comprising a rotatable support, a plurality of rows of abrasive segments arranged thereon to form a cylindrical grinding surface, a freely movable friction member located between and in engagement with the inner faces of adjacent segments, and clamping flanges associated with the rotatable support and adjustably engaging the exposed faces of the end segments of the wheel to press the segments and friction member into frictional contact and to hold them in assembled relation.

2. A wood pulp grinding wheel comprising a drum, a plurality of rows of abrasive segments arranged thereon to form a cylindrical grinding surface, a spindle mountable within the drum to support the same, the inner opposed faces of adjacent segments having a groove, a freely movable friction member

in said groove shaped to engage the sides thereof and permit the segments to lie close together adjacent to the wheel periphery, and clamping flanges adjustably mounted on the spindle and engaging the exposed faces of the end segments which serve to press the segments and friction members into frictional contact and to hold the segments on the drum.

3. A grinding wheel comprising a rotatable support, a plurality of rows of abrasive segments arranged thereon to form a cylindrical grinding surface, a freely movable clamping member between and engaging the inner faces of adjacent segments, clamping members associated with the support and serving to press the segments and the freely movable clamping member together and to hold them in assembled relation, and a filling material in the crevices between the segments adjacent to the grinding surface.

4. A grinding wheel comprising a wide drum, a spindle to support the same, a plurality of rows of narrow abrasive segments on the drum arranged to form a cylindrical grinding surface, the inner faces of adjacent segments which are parallel with the wheel ends being closely positioned and shaped to form a groove therebetween, a freely movable clamping member, which is independent of the drum located in the groove and frictionally engaging the sides thereof, clamping flanges engaging the end faces of the wheel and cooperating with the drum to press the segments and clamping member together and to hold the segments in position, and a cementitious filler in the crevices between the segments which unites them into a rigid wheel structure.

5. A grinding wheel comprising a substantially cylindrical support, a spindle mountable therein, a plurality of annular rows of abrasive segments on said support and arranged to form a cylindrical grinding surface, the inner sides of adjacent rows of segments being shaped to form an annular groove, a freely movable ring in the groove having faces frictionally engaging the segments, clamping flanges independent of said support which are adjustably mounted on the spindle and engage the outer faces of the segments and thereby serve to force the segments and ring into frictional contact, and a cementitious filler in the crevices between adjacent segments which unites the segments and support into a rigid wheel structure.

Signed at Worcester, Massachusetts, this 17th day of May, 1924.
